UNITED STATES PATENT OFFICE.

JAMES LARKEN BIAS, OF GUYANDOTTE, WEST VIRGINIA.

CAR-COUPING.

SPECIFICATION forming part of Letters Patent No. 293,618, dated February 19, 1884.

Application filed December 19, 1883. (No model.)

To all whom it may concern:

Be it known that I, JAMES L. BIAS, a citizen of the United States, residing at Guyandotte, in the county of Cabell and State of West Virginia, have invented a new and useful Car-Coupling, of which the following is a specification, reference being had to the accompanying drawings.

My invention relates to car-couplings, and more particularly to that class known as "automatic couplings;" and it has for its object to provide a device of this character which shall possess superior advantages in point of simplicity, durability, and general efficiency.

The invention consists in the improved construction and combinations of parts hereinafter fully described, and pointed out in the claims.

In the drawings, Figure 1 is a perspective view of a car having my improved coupling applied thereto. Fig. 2 is a vertical section of the same. Fig. 3 is a detail view of the coupling-hook. Fig. 4 is a transverse vertical section of the draw-head, and Fig. 5 is a modified form of coupling-hook.

A represents the car, to the under side of which is secured the usual bumper, B.

C represents the draw-head having the usual link-opening, *a*, and provided on its upper face with a longitudinal slot or opening, *b*. The draw-head is also recessed on its lower inner side, to receive the lower or hooked end of the coupling-hook D. This coupling-hook D is pivoted in the rear lower end of the draw-head by a transverse bolt or rod, *d*, and is cut away to form the hooked portion *d'*. The hook is also formed with the extension *d''*, which projects through the longitudinal slot *b* in the draw-head, and is pivoted to a rod connected to a lever for lifting the hook, which will be more fully described. This hook is made beveled or rounding at its front end, in order that the link, when it strikes against it, may readily raise the same and allow the hooked portion to drop over the link.

E represents a rod or bar, the lower end of which is split to receive the extension *d'* of the coupling-hook, said extension being pivoted therein.

F represents a hand-lever, which is secured in brackets *e e' e''* upon the front side of the

car, the ends of the said lever being bent to form handles. This lever F is provided at about its center with an outwardly-extending arm, *f*.

G represents a rod, which is secured within a bracket, *g*, to the upper end of the car. This rod G is provided with a coil-spring, *g'*, which bears against a burr or washer, *g''*, mounted on the rod G at its lower end, and against the under side of the bracket *g* at its upper end. The lower end of the rod G is perforated, and, together with the arm *f* of the lever F, is pivoted between the arms or split portion of the bracket *f*, formed at the upper end of the rod E.

In Fig. 5 I have shown a modification of coupling-hook, in which case the latter is pivoted in the longitudinal slot of the draw-head. In operation, the end of the link raises the hook, which drops over the same and securely holds it in position.

The operation of the coupling above described is as follows: When the cars are to be coupled, the link of the adjacent car strikes against the beveled end of the coupling-hook and raises the same, which action also causes the spring upon the rod G to be depressed. When the link has fully entered the draw-head, the coupling is forced down by the spring *g'*. When the cars are to be uncoupled, the operation may be effected either from the sides or top of the car—when from the sides, by turning the handle or lever, and from the top by raising the rod G.

It will be apparent that the construction of coupler above described is both simple and effective in its operation.

Having fully described my invention, what I claim as new, and desire to secure by Letters Patent, is—

1. The combination, with the draw-head having the longitudinal slot and a coupling-hook pivoted in said slot, of the rod E, pivoted to the upper end of said hook, and pivoted to the lower end of a rod, G, said rod being secured in a bracket, *g*, and provided with a coil-spring, *g'*, whereby the coupling-hook is held in position and the accidental displacement of the link prevented, substantially as set forth.

2. The combination, with a draw-head having the longitudinal slot *a* and a coupling-hook pivoted therein, of a rod, E, pivoted to the up-

per end of said hook, a lever, F, secured in brackets to the front of the car, and provided with the central arm, f, a rod, G, secured in a bracket to front of the car, its lower end, together with arm f of the lever F, being pivoted to the upper end of the rod E, substantially as set forth.

3. The combination, with a draw-head having the longitudinal slot a and a coupling-hook pivoted therein, of a rod, E, pivoted to the upper end of said hook, a lever, F, secured in brackets to the front of the car, and provided with the central arm, f, a rod, G, secured in a bracket to the front of the car, its lower end,

15 together with the arm f of the lever F, being pivoted to the upper end of the rod E, and a coil-spring mounted on said rod G, its upper end bearing against the bracket g, and its lower end against the burr or washer g², substantially as set forth.

20 In testimony that I claim the foregoing as my own I have hereto affixed my signature in presence of two witnesses.

JAMES LARKEN BIAS.
